SLIDER FOR SEPARABLE FASTENERS

Max H. Lange, Maspeth, N. Y., assignor to Waldes Koh-I-Noor, Inc., Long Island City, N. Y., a corporation of New York.

Application June 1, 1939, Serial No. 276,829

6 Claims. (Cl. 24—205)

This invention relates to separable fasteners of the slide-operated type and more particularly to sliders for such fasteners wherein locking means are incorporated for automatically preventing unintentional movements of the slider along the fastener structure. Such automatic locking means usually comprise a locking member pivotally mounted on the slider body and a spring for normally urging the pivoted locking member into engagement with the interlocking elements positioned within the slider, in combination with, a pull tab associated with the locking member to lift or move the latter out of locking position when it is desired to move the slider in the direction of disengaging the interlocking elements of the separable fastener.

It is the object of the present invention to provide a slider embodying new and improved means for automatically locking the slider against movement along the rows of interlocking elements attached to the stringers of the separable fasteners.

Another object of the invention is to provide an improved locking slider which has a simple and rugged construction, is easy to manufacture and assemble and which will perform its functions without injury or excessive wear of the parts of which the fastener structure is constituted.

A further object of the invention is to provide an improved slider having locking means which will normally engage with the interlocking elements of the separable fastener but which is so constructed and arranged with relation to the pull tab that it may be locked in disengaged position so as to enable free movement of the slider along the rows of elements and to permit opening of the separable fastener by exerting a separating force on the stringers thereof without danger of damaging or ripping off the interlocking elements.

Other objects and advantages of the locking slider of this invention will appear from the following description thereof when taken in connection with the accompanying drawing in which Fig. 1 is a side elevation of a slider embodying the invention with the pull tab partially broken away and shown in the safety lock position; Fig. 2 is a longitudinal sectional view of the slider shown in Fig. 1, illustrating the relation of the locking parts in the safety lock position and showing a few of the interlocking elements of the separable fastener in elevation to illustrate the relation of the locking member with respect to such elements in its unlocked position; Fig. 3

is a view similar to Fig. 2 but showing the pull tab positioned so as to enable the locking member to engage with the interlocking elements of the separable fastener; Fig. 4 is a view similar to Figs. 2 and 3 and illustrates the action of the locking element when the slider is moved to interlock the interlocking elements or to the right as viewed in such figure and Fig. 5 is an end view of Fig. 1, the slider being viewed from the left of Fig. 1.

The separable fastener of the type with which this invention is concerned usually comprises a pair of stringers or tapes having reinforced opposed edges to which the interlocking elements are attached in spaced relation. The interlocking elements of the fastener are all similar in construction and the elements of each stringer are arranged in staggered relation with the elements of the other stringer so that they can come together and interlock properly in interfingered relation. The engagement and disengagement of the interlocking elements are controlled by the movement of a slider which embodies a body portion having substantially parallelly spaced wings and being formed so as to provide a substantially V-shaped channel between the plates through which the interlocking elements pass in the movements of the slider.

In the drawing the spaced wings or plates of the slider are indicated by the numerals 10 and 11, such wings being connected by an integral transverse portion 12 of reduced dimensions. Adjacent to the transverse portion 12 is a transverse member 13 which is wedge-shaped intermediate the plates 10 and 11 (see Fig. 5) and extends up through the upper plate 10 to terminate in an upwardly projecting stud portion 14 of enlarged dimensions and having a shoulder portion which engages with the outer surface of the plate 10 (see Figs. 2 and 3). The member 13 is assembled on the slider body by inserting it through aligned apertures in the plates 10 and 11 and is permanently secured in position by upsetting its lower end against the undersurface of the back or rear plate 11. The stud portion 14 of the member 13 is disposed within one end of a housing or cap member 15 which is secured to the stud portion 14 in any suitable fashion such as by rivets or by indenting it into indentations formed on each side of the stud 14 as is indicated at 16 in Fig. 1 of the drawing. The other end of the housing member 15 is secured to the plate 10 in any suitable manner as by means of a wedge-shaped depending tab 17 integral with the housing member 15 and perma-

nently secured in a wedge-shaped slot 18 formed in the adjacent end portion of the plate 10, as is illustrated in Figs. 2, 3 and 5 of the drawing. Positioned within the housing or cap member 15 and extending longitudinally of the slider, is a locking member 19 which is loosely retained in upright position by the side walls of such cap member and is loosely confined against longitudinal movement within the cap member by the lug portion 14 and the opposite end of the housing member 15 which bears the fastening tab 17.

The locking member 19 is formed from a single piece of sheet metal which is bent or folded lengthwise so that it is substantially U-shaped in transverse section and includes two substantially parallel leg portions 20 and 21 integrally joined by a transverse longitudinally extending portion 22. The locking member 19 is so positioned in the housing member 15 that its leg portions 20 and 21 have their longitudinal edges disposed in opposed relation to the upper surface of the top plate 10, such edge of each leg portion being formed to provide two cam surfaces 23 and 24 intermediate its ends and connected by a depending portion 25 which is spaced from the top plate 10. The cam surfaces 24 of the leg portions extend from the depending portions 25 in a concave manner toward the end of the locking member which lies adjacent to the stud portion 14 to provide two triangularly shaped portions whose apexes 26 bear against the outer surface of the plate 10 when the locking member 19 is horizontally disposed, as is shown in Fig. 2. The cam surfaces 23 of the leg portions extend from the depending portions 25 in the opposite direction and are of smaller radius than the cam surfaces 24. The cam surfaces 23 form the inner edges of a pair of depending portions 27 whose lower ends normally extend into a recess or aperture 28 provided in the top plate 10. The depending portion 27 of the leg 21 of the locking member differs from the depending portion 27 of the leg 20 thereof in that it is additionally provided with a depending detent 29 formed integrally with such portion 27 of the leg and being offset therefrom as is illustrated more clearly in Fig. 5 of the drawing.

The housing or cap member 15 is provided on each side in the region defined by the cam surfaces 23 and 24 with an elongated slot or recess 30 through which extends a transverse portion 31 of a pull tab 32, such transverse portion 31 being disposed between the cam surfaces of the leg portions of the locking member 19 and the exterior surface of the plate 10. The transverse portion 31 of the pull tab is so formed with relation to the cam surfaces 23 of the locking member 19 that when it is positioned between such cam surfaces 23 and the upper surface of the plate 10, as is shown in Fig. 2, the detent 29 will be withdrawn into the aperture 28 of the top plate 10 out of engagement with the interlocking elements 33 of the fastener structure. When such transverse portion 31 of the pull tab is disposed between the cam surfaces 24 and the outer surface of the plate 10 in the position shown in Fig. 3, the cam surfaces 24 are so formed that the locking detent 29 is enabled to come into engagement with the interlocking elements 33 of the separable fastener. Due to the offset nature of the locking detent 29, it engages only with the elements 33 of one row of the fastener, just beyond the outer ends of the interlocking elements in the other row.

Secured at one end between the lug portion 14 and the cap or housing member 15 is a spring 34 which extends longitudinally of the slider and at its other or free end bears on the outer surface of the transverse portion 22 of the locking member 19 and tends to maintain the locking detent 29 in engagement with the interlocking elements of the separable fastener. Thus when the transverse portion 31 of the pull tab is at rest in the region of the cam surfaces 24, the locking detent 29 of the locking member 19 is normally maintained in locking engagement with the interlocking elements under the influence of the spring 34.

From the foregoing description it will be evident that in the normal or at rest position of the parts, the pull tab 32 is in the position illustrated in Fig. 3 of the drawing with the transverse portion 31 thereof disposed in the region defined by the cam surfaces 24 of the locking member 19, such transverse portion 31 functioning as a fulcrum about which the locking member 19 is pivoted in a counter-clockwise direction, as viewed in Fig. 3, under the influence of the spring 34 so that the locking detent 29 of such member is in locking engagement with the interlocking elements of the separable fastener, whereby movement of the slider in the opening direction or to the left as viewed in Fig. 1 is prevented. When it is desired to open the interlocking elements of the separable fastener, the pull tab 32 can be operated so that the transverse portion thereof bears against the depending portions 25 of the locking member 19, the cam surfaces 24 being so formed at this region that under the force exerted by the transverse portion 31 of the pull tab, the locking member is lifted sufficiently to withdraw the locking detent 29 thereof from engagement with the interlocking elements. Due to the fact that during this action the points 26 of the locking member 19 come into engagement with the upper surface of the plate 10 of the slider, the locking member moves with a pivotal action about such points 26 against the tension of the spring 34. By exerting sufficient force to move the transverse portion 31 of the pull tab past the depending portions 25 of the locking element, such transverse portion comes into the region defined by the cam surfaces 23 of the locking element wherein it is retained so that the user is enabled to unlock or disengage the interlocking elements simply by pulling the stringers apart without any danger of the locking detent coming into engagement with the interlocking elements rushing through the slider. During the passage of the transverse portion 31 of the pull tab into the safety lock formed by the depending portions 25 and the cam surfaces 23, the locking detent 29 is withdrawn to its outermost position and then returned slightly when the transverse portion 31 is in its safety lock position, such return however not being great enough to enable the locking detent 29 to come into engagement with the interlocking elements of the slider. The movement of the transverse portion 31 past the depending portions 25 of the locking element is accomplished with a snap action under the influence of the spring 34.

When the slider is actuated to close the fastener, the pull tab is usually positioned as is shown in Fig. 4, the transverse member 31 thereof through the force exerted on such tab lifting the end of the locking member adjacent to the lug portion 14 up against the body portion of the spring and pivoting the locking member about

such end as a fulcrum against the tension of the spring 34 to lift the locking detent 29 thereof out of its normal locking position. The locking member preferably is so designed with respect to the other parts that this action of the pull tab entirely withdraws the locking detent 29 into the recess 28 out of contact with the interlocking elements 33 thereby preventing dragging of the detent along the upper surfaces of the interlocking elements as the latter are being interengaged. In order to obviate any possibility of the locking detent 29 catching the interlocking elements as the slider is moved in the closing direction or to the right, as viewed in Fig. 4, such detent is provided with an inclined lower edge surface 35 which enables the interlocking elements to cam the locking detent out of their path, as will be readily understood from a study of Figs. 3 and 4 of the drawing.

It will be observed therefore that in the foregoing construction the interlocking element is an independent, self-contained, rigid member which is loosely enclosed within a casing member and which during the several operations of the pull tab, is fulcrumed about three points, namely, the transverse portion 31 of the pull tab 32 when the slider is stationary with the detent engaging the interlocking elements as is illustrated in Fig. 3; the portions or points 26 of the locking element when the pull tab is operated to move the slider to open the interlocking elements of the separable fastener and the top edge portion of the locking element when the pull tab is operated to move the slider in the closing direction or to the right as illustrated in Fig. 4. These several operations of the rigid locking member are accomplished because such member by reason of its being loosely mounted within the casing member is in the nature of a float unit and is so arranged with respect to the spring 34 whose free end slidably engages the outer longitudinal edge portion of the float unit at a point above the detent 29 thereof to normally urge the latter to its locking position, and the transverse portion 31 of the pull tab, that in the longitudinal movements of such portion 31 and the forces exerted thereon during the operations of the pull tab and consequently the slider, such float unit is caused at times to seesaw about the transverse portion 31 and at other times to move about the legs 26 or the top edge of the float unit above the legs 26, depending upon the position of the transverse portion 31 of the pull tab with relation to the float unit and the direction of force applied to such transverse portion. The above construction is also designed to maintain the position of the pull tab with respect to the locking element so that the latter is retained in unlocked position to enable free movement of the slider on the rows of interlocking elements either in the closing or opening directions and in the latter case enabling the fastener structure to be opened simply by forcing apart the tapes or stringers thereof.

While I have in this application specifically shown and described a preferred embodiment of my invention, it will be understood that modifications and changes may be made in such embodiment without departing from the spirit of the invention or the scope thereof as defined in the following claims.

I claim:

1. A slider for separable fasteners comprising a pair of plates spaced to receive the interlocking elements of the fastener, a housing fixed to one of said plates and having elongated longitudinally extending openings on each side thereof, an independent, self-contained, rigid member extending longitudinally of the slider and loosely mounted within said housing for rocking movement with relation to said plate, said rigid unit having a rigid detent at one end projecting into an aperture in the associated plate and having at its other end a rigid portion adapted, in at least one of the positions of the rigid unit, to bear in disconnected relation against a fixed surface portion within said housing to afford a fulcrum for the rigid unit, the inner longitudinal edge of said rigid unit being provided with a cam surface approximately as long as the longitudinal openings in said housing, resilient means normally urging said detent into locking engagement with the fastener elements in the slider, a pull tab having a transverse member extending through the openings in said housing and between the cam surface of said rigid unit and the associated plate, said cam surface being arched and coacting with said transverse member of the pull tab to cause said rigid unit to rock about its fulcrum portion in the operations of the slider.
2. A slider for separable fasteners comprising a pair of plates spaced to receive the interlocking elements of the fastener, an independent, self-contained, rigid float unit overlying one of said plates and loosely mounted for rocking movement with relation to such plate, means secured to said plate for loosely confining said float unit in its rocking movements, said float unit extending longitudinally of the slider and having a rigid detent at one end adapted to project into an aperture in said plate and having at its other end a plurality of spaced surface portions adapted to rest against said plate and confining means to afford fulcrum points for the float unit, and said float unit having an inner longitudinal edge including an arched portion to provide a cam surface, resilient means normally urging said detent into engagement with fastener elements in the slider, a pull tab having a transverse member extending between said float unit and the associated plate, said transverse member coacting with the cam surface to cause said float unit to pivot about its fulcrum portions when pulling forces are applied to the pull tab in the operations of the slider.
3. A slider for separable fasteners comprising a pair of plates spaced to receive the interlocking elements of the fastener, a housing fixedly mounted on one of said plates, an independent, self-contained, rigid float unit overlying said plate and loosely mounted within the housing for rocking movement with relation to said plate, said float unit having a rigid leg at one end extending towards the exterior surface of said plate and in at least one of the positions of the float unit resting against said plate surface to afford a fulcrum point for the float unit, said float unit having a rigid detent at its other end projecting into an aperture in said plate, the outer longitudinal edge portion of said float unit being shaped for engagement with a spring member and the inner longitudinal edge of said float unit intermediate said leg and detent including an arched portion spaced from the exterior surface of said plate and forming a cam surface, a spring member carried by the slider and having one end engaging with and bearing against the outer longitudinal edge of said float unit at a point adjacent to the detent end thereof to normally urge said detent to its locking position, and a pull tab having a transverse member extending be-

tween said float unit and said plate and confined between said leg and detent, said transverse member coacting with the inner arched edge portion of said float unit upon movement of the pull tab to withdraw said detent from its locking position against the yielding pressure of said spring member.

4. A slider for separable fasteners comprising a pair of plates spaced to receive the interlocking elements of the fastener, a housing fixedly mounted on one of said plates, an independent, self-contained rigid float unit overlying said plate and loosely mounted within the housing for rocking movement with relation to said plate, said float unit having an outer longitudinal edge portion shaped for engagement with the spring member and being recessed on its inner longitudinal edge to form an inwardly extending rigid projection at one end thereof and an inwardly extending rigid detent at the other end thereof, said projection overlying the exterior surface of said plate and in at least one of the positions of the float unit resting against said plate surface to afford a fulcrum point for the float unit, said rigid detent projecting into an aperture provided in said plate, a pull tab having a transverse member extending through said housing and between said float unit and said plate and having a range of movement longitudinally of the slider between said projection and said detent, said transverse member coacting with the inner longitudinal recessed edge portion of said float unit intermediate said projection and detent to withdraw the latter from its locking position when a pulling force is applied to said pull tab, and a spring member affixed at one end to said slider and overlying said float unit, the free end of said spring member slidably engaging and bearing against the outer longitudinal edge portion of said float unit at a point adjacent to the end of the range of movement of said transverse member in the direction of said detent to normally urge the latter to its locking position.

5. A slider for separable fasteners comprising a pair of plates spaced to receive the interlocking elements of the fastener, a lug projecting outwardly from one of said plates, a housing fixedly attached to said lug and said plate, an independent, self-contained, rigid float unit overlying said plate and loosely mounted within said housing for rocking movement with relation to said plate, said float unit having an outer longitudinal edge portion shaped for engagement with a spring member and being arched on its inner longitudinal edge to form an inwardly projecting, rigid leg at one end thereof and an inwardly extending, rigid detent at the other end thereof, said rigid leg being positioned adjacent to said lug and overlying the exterior surface of said plate and in at least one of the positions of said float unit resting against said plate surface to afford a fulcrum point for the float unit, said

rigid detent projecting into an aperture provided in said plate, a spring anchored at one end between said lug and housing and extending over the outer longitudinal edge of said float unit to a point adjacent to the detent end of said float unit, the free end of said spring being in slidable engagement with and bearing against the outer longitudinal edge portion of said float unit to normally urge said detent to its locking position and a pull tab having a transverse member extending through said housing and between said float unit and plate and having a range of movement longitudinally of the slider between said leg and detent, said transverse member being adapted to coact with the inner arched edge portion of said float unit intermediate said leg and detent to withdraw the latter from its locking position against the pressure of said spring when a pulling force is applied to said pull tab.

6. A slider for separable fasteners comprising a pair of plates spaced to receive the interlocking elements of the fastener, a lug projecting outwardly from one of said plates, a housing enclosing said lug and being fixedly attached thereto, an independent, self-contained, rigid float unit overlying said plate and loosely mounted within said housing for rocking movement with relation to said plate, said rigid float being positioned intermediate one end of said housing and said lug and consisting of a U-shaped plate having an outer folded longitudinally extending edge affording an engaging surface for a spring member and its parallelly disposed longitudinally extending inner edges provided with a pair of inwardly projecting legs at one end and a pair of inwardly extending projections at its other end, said legs being positioned adjacent to said lug and adapted to bear on the exterior surface of said plate in at least one of the positions of the float unit to afford fulcrum points for the float unit and at least one of said projections being provided with a detent adapted to project through an aperture in said plate, a spring anchored at one end between said lug and housing and extending over said float unit to a point adjacent to the detent end of said float unit, the free end of said spring being in slidable engagement with and bearing against the outer folded longitudinal edge of said float unit to normally urge said detent to its locking position, and a pull tab having a transverse member extending through said housing and between said float unit and plate and having a range of movement longitudinally of the slider between the legs and projections of said float unit, the inner longitudinal edge portions engageable by said transverse member being arched to provide two longitudinally extending cam surfaces and coacting with said member to withdraw the detent from its locking position against the pressure of said spring.

MAX H. LANGE.
